William Medd Watson

UNITED STATES PATENT OFFICE.

WILLIAM MEDD WATSON, OF TONICA, ILLINOIS.

IMPROVEMENT IN GRAIN-SEPARATORS.

Specification forming part of Letters Patent No. 33,617, dated October 29, 1861.

To all whom it may concern:

Be it known that I, WILLIAM MEDD WATSON, formerly WILLIAM WATSON, of Tonica, in the county of La Salle and State of Illinois, have invented a new and useful Machine for Dividing Mixed Grain, but especially to Separate Oats from Wheat, of which the following is a full, clear, and exact description, reference being had to the accompanying drawings, which make part of this specification, and in which—

Figure 1 represents a longitudinal section of my grain-divider. Fig. 2 represents a top view of the same, with the endless propelling-apron removed to expose the perforated dividing-plate and the rollers by which the endless propelling-apron is stretched and carried. Fig. 3 represents a piece of a dividing-plate of full size which I have had successfully at work to show the actual size and relative position of perforations that have been found in practice adequate to the complete division of oats and spring wheat mixed in the proportion of three parts, by measure, of the former to seven parts, by measure, of the latter, the mixture being unmarketable as wheat, even at a price proportionate to the quality of wheat in the mixture, because of the difficulty of separating the oats and their injury to the quality of the flour when the mixture is ground.

The grains of wheat and oats differ greatly in shape and proportions. The form of a wheat-grain is nearly ellipsoidal, or egg-shaped, its longest diameter or length being about double its shortest diameter or thickness. The form of an oat-grain approaches to that of an elliptic spindle with one end thicker and much heavier than the other. Its thickness at its largest part is about the same as that of a wheat-grain and its length is about double that of a wheat-grain. The wheat seems short and thick and the oat comparatively long and slender. I have taken advantage of this difference in the form of the two kinds of grain to separate them; and my invention is founded upon the theory that if a mixture of those two grains be rolled in a stratum of not more than one grain in thickness over a plane surface by the continuous motion of another parallel surface pressing against the grains, so as to roll them or slide

them by friction, and thus carry them forward, and the lowermost of these plane surfaces be perforated with numerous holes of a diameter about equal to three-quarters of the average length of the wheat-grains to be divided from the grains of oats, and those holes are in such position that several of them will be in the path of each wheat-grain in crossing the plane, and the wheat will all pass through the holes, while the oats, being longer, will roll or slide over the holes to the end of the plane, by which means the two kinds of grains are completely divided. If the wheat and oats were caused to slide or roll over the perforated plane by a jarring motion or by a rake or otherwise without at the same time pressing the oats so as to compel them to lie flat, whenever the heavy end of an oat overlaid one of the holes in the plane it would descend by its gravity tilting up the light end and diving through the hole endwise and passing down among the wheat-grains. Thus it will be seen that the essence of my invention consists in keeping such pressure upon the grains of oats while passing over the perforated plate with the wheat as will prevent them from turning sidewise and passing through the wheat-holes, their length being so great that they cannot pass through the holes sidewise.

The machine shown in the drawings consists of a strong oblong frame A, a hopper B, to contain the mixed grain to be divided, a perforated plate C, to screen out the wheat and retain the oats, an endless apron D, stretched round rollers above the perforated plate, the apron being of a width equal to that of the plate, with which its lower portion is parallel and in close proximity throughout the whole extent of the perforated surface. The apron may be kept properly stretched by springs arranged between the rollers to press them apart, the journals of the rollers to facilitate this object being set in sliding boxes. If preferred, the boxes may be set by screws instead of springs at the proper distance apart.

The apron may press upon the perforated plate with its own or any required weight by giving to the boxes of the rollers a vertical sliding motion, supporting them on springs and pressing them down by a screw or by another spring more powerful than the sup-

porting-springs, which should be barely strong enough to counterbalance the weight of the rolls and apron. By regulating the pressure of the downward-acting spring the apron will bear with greater or less force upon the perforated plate. Care must be taken not to make the pressure heavier in any case than is necessary to keep the oats lying on their sides upon the perforated plate, as greater pressure than this would cause undue wear and tear and consumption of power.

The endless apron and rollers may be arranged without the vertical adjustment described, and instead the perforated plate may be made adjustable by screws toward and from the endless apron, or it may rest on springs that press it toward the apron with either a fixed force or one which is rendered variable by regulating the tension of the spring by any common and suitable adjusting apparatus. A stop should be so arranged as to prevent the apron and perforated plate from pressing hard together. Indeed, to produce the best effect they should not approximate nearer than the thickness of the smallest grains of oats, as they have no function to perform that requires them to approach nearer together.

The machine is simplified by arranging the perforated plate and apron at a fixed distance apart equal to the smallest oats, leaving the elasticity of the apron and plate to yield sufficiently to allow the passage of the larger oats between them.

The apron may be made of stout duck, lined with felt cloth to make it elastic, or it may be made of soft leather or india-rubber; and to relieve it from the wear and tear produced by stretching it round and driving it by the rollers, the apron may be secured to and carried by leather belts encircling the rollers.

The rollers may be turned by hand by means of a crank affixed to the outer end of the journal of one of them; or a pulley or cog-wheel may be affixed to the same part, to be turned by any convenient prime mover. This application of rotating motion to one roller from the connection of the two rollers by the endless band insures a corresponding motion of both rollers and the band.

The perforated plate may be made of any thin metal. I prefer sheet-iron, which should be stiffened by ribs attached to its under side. If this plate should be cast, the ribs would of course be cast in one piece with it. The top of the plate should be even and free from angles or roughness. The holes I prefer to make round. Their edges on the upper side of the plate should be rounded and smooth. They should be of the size represented in Fig. 3 of the drawings for cleaning wheat the average length of whose grains is one-fourth more than the diameter of the hole. For

wheat of considerably greater or less average length, plates with holes of a correspondingly enlarged or diminished diameter must be provided. Three or four plates with different-sized holes will probably be sufficient for dividing the mixtures of all the different varieties of wheat and oats that are offered to any great extent for sale. The holes in one row should be placed opposite the spaces between the holes in the next row, and the spaces between the holes should be exactly equal to the diameter of the holes. This arrangement of the holes renders it difficult for a grain of wheat to get across the plate without falling through.

The machine should be provided with a hopper of any convenient size to contain the mixed grain to be divided. At the lower side of the hopper there should be a vibrating shoe of the usual form to discharge the wheat in an even stream from the hopper and feed it between the apron and perforated plate. The shoe of the hopper may be vibrated by motion derived from the rollers that drive the apron. The grain as it falls from the hopper is carried by the motion of the apron bearing on it to and across the perforated plate, and as the grain passes over the plate the wheat drops through, or, rather, is pressed through, the holes very quickly, so that little of it reaches the middle and very little or none gets across the plate. The oats being kept by the pressure of the apron lying down on their sides upon the plate and being too long to pass sidewise through the holes, they are carried by the motion of the apron across the plate while thus held down and discharged at the end into a spout E, provided for the purpose. A plate from one to three feet in length is sufficient to divide any mixture of wheat and oats. For plump short wheat and long oats a foot is sufficient for the separation. Long shriveled wheat and short plump oats require a longer plate. The wheat, dropping through the plate, lodges in a receptacle beneath, while the oats, being retained, as before explained, are carried to the end of the plate by the apron and discharged by the spout in a heap by themselves on the floor or into any convenient receptacle.

What I claim as my invention, and desire to secure by Letters Patent, is—

A machine composed of a pressure-carrier, a perforated surface, and a feeding mechanism for dividing mixed grain and depositing the several kinds in separate places, substantially as described.

In testimony whereof I have hereunto subscribed my name.

WILLIAM MEDD WATSON.
